BIRD FEEDING STATION

Albert B. Moore, Falls Village, Conn., assignor to Mold-Craft Inc., Port Washington, Wis., a corporation of Wisconsin

Application December 15, 1955, Serial No. 39,336

Term of patent 7 years

(Cl. D31—2)

Fig. 1 is a perspective view of a bird feeding station embodying my new design;

Fig. 2 is a front elevational view thereof;

Fig. 3 is a rear elevational view;

Fig. 4 is an elevational view looking at one edge;

Fig. 5 is an elevational view looking at the opposite edge; and

Fig. 6 is a bottom view.

I claim:

The ornamental design for a bird feeding station, substantially as shown.
